57 # UNITED STATES PATENT OFFICE.

JAMES H. GROVE, OF OMAHA, NEBRASKA, ASSIGNOR, BY MESNE ASSIGNMENTS, TO AMERICAN ARCH COMPANY, OF NEW YORK, N. Y., A CORPORATION OF NEW YORK.

LOCOMOTIVE-BOILER FURNACE.

4,033,006.

Specification of Letters Patent. Patented July 16, 1912.

Application filed October 19, 1908. Serial No. 458,524.

To all whom it may concern:

Be it known that I, JAMES H. GROVE, a citizen of the United States, and a resident of Omaha, Douglas county, Nebraska, have invented certain new and useful Improvements in Locomotive-Boiler Furnaces, of which the following is a full, clear, and exact description, such as will enable others skilled in the art to which it appertains to make and use the same.

My invention relates to improvements in locomotive boiler furnaces and the object of my invention is to so improve locomotive boiler furnaces as to adapt them to the burning of lignite.

This present invention is a modification of that which is shown and described in my pending application No. 387,442, entitled "Lignite burning furnaces", filed August 7, 1907.

My invention consists generally in locomotive boiler furnaces comprising a firebox having a flue sheet at one end and a fuel door at the opposite end, in combination with an inclined front arch abutting the flue sheet and extending rearwardly and upwardly therefrom, said arch being constructed to introduce heated air into the central portion of the firebox and to deflect the same downwardly toward the grate and the rear end of the firebox, a plurality of transverse arches composed of refractory material arranged above and back of the rear end of the front arch; all as hereinafter more fully described and particularly pointed out in the claims.

My invention will be more readily understood by reference to the accompanying drawings, forming a part of this specification and in which—

Figure 1 is a vertical longitudinal section of a locomotive boiler furnace embodying my invention. Fig. 2 is a plan view thereof, the crown sheet of the furnace being broken away to disclose the construction and positions of the several refractory arches. Fig. 3 is a vertical section on the line X—X of Fig. 1. Fig. 4 is a smaller vertical section of my invention embodied in a firebox of the narrow type.

In the drawings 2 represents the shell of the boiler; 3 the flues; 4 the flue sheet; 5 the rear sheet of the fire box; 6 the door opening; 7 the fuel door which closes the opening; 8 the side sheets; 9 the crown

sheet and 10 the grate. In the front part of the firebox, extending rearwardly from the flue sheet is an inclined refractory arch, A. This is of the well known Wade & Nicholson hollow arch type, being provided with a plurality of air passages, a, which receive air through the thimbles, 11, at the lower end of the arch. The air is heated while passing through the arch A and on emerging from the upward ends of the passages, a, impinges upon the deflector bricks, a', and is thereby turned or deflected downwardly toward the grate and the rear end of the firebox.

B is an arch composed of refractory bricks extending between the side sheets, 8, 8, at a point adjacent to and preferably slightly above the rear end of the hollow front arch A. Only a small throat or opening, C, is left between the arches A and B. Arch, B, is preferably formed so that the longitudinal lines on the under surface are horizontal (as shown in Fig. 1). The rear surface, b', is preferably vertical. It will be noted that a large space is left between the top of the arch, B, and the crown sheet, 9 and in this space I arrange another or upper refractory arch, D, substantially identical with the arch B. The throat or opening, E, between the top of the arch B and the bottom of the arch D is preferably larger than the throat C. The arches A, B and D being of refractory material take on the high temperature of the firebox and the arches B and D attain the highest temperature of the box. These arches B and D together present in the aggregate a considerable mass of refractory material at the throat or opening of the furnace. The term "throat" as here used defines in a general sense the space between the rear or upper end of the main arch or deflector, A, and the crown sheet of the box. The special advantage of a hot mass of bricks at this point is that when heated as described they tend to maintain the temperature in the upper part of the box at all times, and particularly at the times when the fuel door is opened. The heated air from the front arch in descending toward the grate accomplishes several important results.

First, its admission substantially at the center of the furnace reduces the vacuum on the surface of the bed of lignite on the grate, 10. Second, the downward moving streams of air counteract and tend to reduce the ve-

lacity of the upward moving streams of gases from the fuel. Third, the hot air quickly admixes with the combustible gases and particles in the lower part of the furnace beneath and back of the arch, markedly augmenting combustion. Fourth, the streams or sheets of air from the front arch are swept upwardly and across beneath the throat C, with the effect that the combustibles which pass through the throat C are enriched by admixture with the hot air and to the further effect that quantities of hot air are admixed with the firebox gases back of the arches B and D. By impact against these arches a thorough admixture of air and gases is enforced and accomplished. It will be noted also that quantities of air are supplied at the more distant throat, E, and as the main stream of firebox gases is interrupted and contracted at the throat it follows that the air from the front arch is admixed therewith most advantageously. In this manner I accomplish a substantially perfect combustion of gases and combustible particles from lignite; thereby attaining the first or primary object of the invention, and as an incident thereto I set up currents of hot air and firebox gases contrary to the general flow of gases with the result that the light fuel particles that are lifted from the grate are thrown down and do not escape through the throat of the furnace. The bottom and rear sides of the arches B and D serve as deflectors and aid in the baffling and returning the fuel and ashes to the grate. In this manner I attain the second important object of my invention, to wit, the burning of lignite fuel wholly within the firebox and the prevention of its discharge at the smokestack of the locomotive. I prefer that in all cases the arch B shall be at such distance from the top of the arch A that cinders and fuel carried over the arch B will fall into the firebox through the throat C, and it is essential that passages between the arches shall be abruptly enlarged at the outlet side thereof to insure quick expansion of the congested gases, and the consequent lessening of their velocity, whereby the heavier particles are freed and allowed to fall back into the firechamber.

As various modifications of my invention will suggest themselves to one skilled in the art I do not confine myself to the specific structure herein shown and described.

Having thus described my invention I claim as new and desire to secure by Letters Patent:

1. A locomotive fire box in combination with an inclined refractory arch arranged in the front part of said firebox and adapted to introduce heated air into the central portion of the firebox and deflect the same downwardly toward the grate and rear end of the firebox and a plurality of refractory

vertical arches arranged in the upper part of the firebox spaced to the rear from the rear end of the front arch, substantially as described.

2. A locomotive firebox having a flue sheet at one end, a fuel door at the other end and a grate near the bottom thereof, in combination with an inclined refractory front arch interposed between the flue sheet and the grate of the firebox, said arch having conduits adapted for the passage of air therethrough, the exit end of said conduits being formed to deflect the air downward toward the grate and at about the center of the firebox, a refractory arch extending across the firebox back of the first mentioned arch, and a third refractory arch above the second mentioned arch, the arrangement of said arches being such that narrow throats or passages are formed therebetween connecting the portion of the firebox which is back of and below said front arch with the portion which is above and in front of said front arch, substantially as described.

3. A locomotive boiler firebox in combination with an inclined front arch therein, said arch having conduits adapted for the passage of air therethrough, the exit end being formed to deflect the air downward toward the grate at about the center of the firebox, a refractory arch bridging the firebox above and back of said front arch and a further refractory arch dependent from the top of the firebox above the second mentioned arch, restricted throats being formed between said arches, as and for the purpose specified.

4. A locomotive boiler firebox having a flue sheet at one end, a fuel door at the other end and a grate near the bottom, in combination with an inclined refractory arch, there being a combustion chamber above said inclined arch and a fuel chamber beneath it, said arch having air passages communicating with air tubes in the shell of the firebox, said air passages opening into the fire box at substantially the center thereof and being adapted to deflect the air downwardly toward the grate, a vertical refractory arch extending across the fire box back of the first mentioned arch and a third refractory arch above the second mentioned arch projecting downward from the crown sheet, the arrangement of these arches being such that narrow passages are formed between the fuel chamber and the combustion chamber, substantially as described.

5. A locomotive fire box having a flue sheet at one end, a fuel door at the other end, and a grate at the bottom thereof, in combination with an inclined refractory front arch interposed between the flue sheet and the grate dividing the fire box into a fuel chamber below and a combustion chamber above the arch, said arch being adapted

to introduce heated air and project it downwardly from the upper end thereof, a plurality of refractory vertical baffle arches projecting across the fire box above and back of said front arch, arranged out of alignment, thereby forming passages between the fuel chamber and the combustion chamber therein, said passages being arranged and adapted to impart a zig-zag flow to the fire-
10 box gases, substantially as described.

6. A locomotive fire box in combination with an inclined front arch therein, said arch being adapted to introduce heated air and project it downwardly from the upper
15 part of said front arch, an upper and a lower vertical baffle arch arranged in the upper portion of the rear end of the fire box, said lower arch being spaced to the rear from the rear end of said inclined arch and
20 said upper arch having its forward face substantially in alignment with the rear end of said inclined arch.

7. A locomotive firebox having a flue sheet at one end, a fuel door at the other
25 end and a grate at the bottom thereof, in

combination with an inclined refractory front arch interposed between the flue sheet and the grate dividing the firebox into a fuel chamber below and a combustion chamber above the arch, said arch having air inlet ducts therein adapted for transmitting, heating and discharging air rearwardly and downwardly into the firebox and a pair of refractory vertical baffle arches extending across the firebox above and back of said
30 front arch, one lying close to the top of the firebox and the other spaced slightly beneath the former and substantially equidistant from the upper baffle arch and the front arch thus providing a pair of throats
35 leading from the fuel chamber to the combustion chamber.

In testimony whereof, I have hereunto set my hand, this 10th day of October, 1908, in the presence of two subscribing witnesses.

JAMES H. GROVE.
